UNITED STATES PATENT OFFICE.

JOHN B. TERRY, OF HARTFORD, CONNECTICUT.

MACHINE FOR STICKING PINS.

Specification of Letters Patent No. 10,372, dated January 3, 1854.

To all whom it may concern:

Be it known that I, JOHN B. TERRY, of the city of Hartford, State of Connecticut, pin manufacturer, have invented, made, and applied to use certain new and useful Improvements in Machinery for Sticking Pins in Rows into Paper; and I hereby declare that the following is a full, clear, and exact description of the construction and operation of the same, reference being had to the annexed drawing, making part of this specification, wherein—

Figure 1, is a side elevation as with the frame on this side removed; Fig. 2, is a front elevation; Fig. 3, is a plan of the bed and jaws for crimping the paper as with the conductor and feeding wheel removed; Fig. 4, is a sectional elevation of the jaws and parts attached and Fig. 5, is a cross section as through the line A B, of Fig. 1.

The like marks of reference denote the same parts.

a, is the frame of the machine of wood or metal with two standards *b*, at the back end carrying by a frame 1, the hopper *b*¹, one end of which rests on the upper end of the inclined conductor *c*, which at this point is formed as a trough, with a split in the bottom large enough to allow the shafts 20 of the pins to pass into the split while the heads are retained above. The upper end of the conductor has a click or ratchet 2, resting on a ratchet pinion *c*¹, on a shaft in the standards *b*, to which a rotation is given by any proper means so as to shake or jar both the hopper and conductor, and cause the pins that are placed in the hopper gradually to fall into the conductor and slide down, and any pins that are not caught 35 by their heads and slide in the conductor are passed over the end of the trough *c*, into a suitable receptacle 3 shown here as on a standard attached to the frame *a*, and a curved guard *c*², allows the heads of the 40 pins to pass but prevents any surplus of pins from sliding down on the lower part *c*³, of the conductor, which is attached to a vertical split conductor *d*¹, supported by a standard to the bed *h*. The junction between 45 this inclined and vertical conductor is made by a split roller so set as to match with the faces of the conductors and is on a shaft with a pulley 4, to which motion is given by a belt or other means so that the surface 50 of the roller travels quicker than the speed of the pins as they slide down the conductor

*c*³, by this means they are compelled to turn from a vertical to a horizontal position and are forced down the vertical part *d*¹, of the conductor and fed quicker into the machine than they could be by their gravity only.

e, is a wheel on a horizontal shaft 5, in bearings 6, on the bed *h*, that sits against and under the lower end of the conductor *d*¹, which is curved to correspond with and sit close onto the wheel, and continued as an inclosing shield *e*¹, sitting against the wheel nearly down to the bed *h*, and a shield 60 7, prevents the heads of the pins protruding from the conductor or wheel *e*. The edge of this wheel *e*, has notches or grooves of the size to receive one pin, cut across its circumference, at proper distances apart, and the diameter of this wheel is such as to receive notches for three, four or more rows 65 of pins around its circumference. To this wheel *e*, an intermittent rotary motion is given so as to bring each successive row of pins into a proper place to be stuck into the paper.

*e*², is a ratchet wheel on the shaft 5, with as many teeth as there are rows of grooves for the pins in the circumference of the wheel *e*.

*e*³, is a radius bar on the end of the shaft 5, carrying the click 8, kept to the wheel *e*², by a spring 9.

10 is a curved keeper piece or circular slide attached to the end of the bar *e*³, passing within an opening or mortise in the guard *e*¹, and sitting close against the wheel *e*, see dotted lines in Fig. 2.

f, is a descending rod attached at its upper end to the bar *e*³, the lower being connected at 11, to the side of a radius bar *f*¹, on a center 12, on the frame *a*. To the bar *f*¹, is a vertical rod with a helical expansive spring *f*², around it abutting at the lower end on a cross piece 13, through which the rod passes freely.

g, is a horizontal shaft supported in bearings 14, on the frame *a*, on the end of which is a crank handle or pulley 15, to which power is applied to rotate the shaft.

*g*¹, is a cam attached on the shaft *g*, which taking the bar *f*¹, depresses it the proper amount, and sliding off the end allows the spring *f*², to throw the bars *f*¹, and *f*, up with a sudden motion taking up another notch on the wheel *e*², and in its descent by 110 the action of the cam rotating the wheel *e*, each notch of which as it passes under the

conductor d^1 , receives a pin, which pins are kept in place by the guard e^1 , and sustained by the circular slide 10,—sitting close to the wheel e , and moving with it when operated on by the click 8, and bar e^3 —retains the pins in the notches in the wheel e , until the cam g^1 , sliding off the bar f^1 , allows the spring f^2 , to throw up the click and bar e^3 , with a sudden motion, which also draws 5 with it the circular slide 10, allowing the pins to drop onto a jaw 17 set in slides on the bed h , as hereafter described. It will thus be seen that the wheel e , is filling with a slow motion while the pins are being 10 stuck and then the pins are dropped suddenly ready to be stuck, in the next row, thereby saving the time required by the reciprocating bed in being filled before the pins are stuck.

15 20 25 30 35 40 45 50 55 60 65 70 75 80 85 90 95 100 105 110 115 120 125 130

16, are supports connecting and sustaining vertical dividing plates i , resting on the jaw 17 and extending up to the wheel e , and having notches next the wheel e , to pass the circular slide 10. The dividing plates i , occupy spaces as shown, between where each pin is dropped, so that each pin falls onto the jaw 17 between the dividing plates. i^1 , is a flat bed set in slides 18, having fingers i^2 to pass between each pair of dividing plates i , and press the pin forward through the paper which is crimped and prepared to receive the pin as hereafter set forth. The bed i^1 , receives an alternating motion by a connecting rod i^3 , attached to a standard 19, on the under side of the bed i^1 , which rod i^3 , is connected at the other end to a vertical radius bar i^4 , jointed at its upper end to a standard on the bed h .

k , is a miter wheel on the end of the shaft g , gearing to a similar wheel k^1 , on a cross shaft l , in bearings 21, on the frame a , on which shaft is a cam l^2 , operating in its rotation against the bar i^4 , to draw the bed i^1 , forward and stick the pins and then taking a projection 22, on the side of the rod i^3 , the cam l^2 , forces the bed i^1 , back again.

The jaw 17 on the side opposite to the sliding bed i^1 , has a cross piece 25 raised slightly from its surface with grooves cut 55 into and through the cross piece 25, opposite and in the line of each pin as it is dropped onto the jaw 17. This jaw 17 is in slides 24, which are a continuation of the slides 18, on each side, which also receive between them a fixed jaw or cross piece 23, and also the ends of another sliding jaw 26. This jaw 26 and cross piece 23 have deep 60 grooves or notches cut in them to correspond with the grooves in the cross piece 25, on the jaw 17.

27 is a sliding bar fixed on the under side of the jaw 17, and 28 is a similar bar fixed on the under side of the jaw 26, these sliding bars 27, and 28, pass through slides 29, 65 on the bed h , and serve as guides to cause

the jaws 17, and 26, to remain parallel to the cross bar 23. 30, is a curved bar attached to the slide 27 and passing over and near the side of the shaft l , and 31, is a curved bar attached on the under side of the slide 28, turning down and stopping short of the shaft l , on which shaft are two small cams 33, set on opposite sides of the shaft so that each rotation of the shaft l , the jaws 17 and 26, are drawn close onto the bar 23, and as the cams relieve the bars 30 and 31 the vertical parts are drawn together and the jaws separated by a spring 32; or the bars 30 and 31 may be formed as forks on their ends sitting over the shaft so that the cams in their rotation both close and open the jaws 17 and 26.

m , is a cam on the shaft l , taking against a vertical bar n , which is kept to the cam by a spring 34, and at the upper end is connected with a frame u^1 , set and moving on centers 35 on the bed h , the end of this frame near the wheel e , is formed as a cross bar o , that when depressed coincides with the cross bar 23, and on the sides of this bar o , are plates of metal forming a rabbet that passes down on each side of the bar 23. 36, is a roller on the side of the crimping bar o , next the wheel e . The operation of this part is that the cams 33, and m , being timed with the other parts and with themselves, the paper being led from the roll p , over the roller 36, and drawn out as hereafter set forth the crimping bar o , depresses the paper over the bar 23, and holds it there until the jaws 25 and 26, coming up and by small pins projecting from their faces hold the paper, at the same time the cam m , passing clear of the lever n , the spring 34, raises the crimping bar o , out of the way and the jaws 17 and 26, come tight against the bar 23, holding the paper at right angles to the points of the pins as they are forced through the grooves in the bar 23, 25 and 26, into and through the paper. The jaws 17 and 26, now opening allow the paper to be drawn along for another row as next shown.

q , is a roller in journals 37 on the frame a , and r , is another beneath, the shaft of which passes through the frame and has a ratchet wheel 38, outside, see dotted lines in Fig. 1, with a click on a rod 39, connected to the upper end of a bar r^1 , that is jointed at the lower end to the frame a , and has a contractile spring 40 to keep the bar r^1 , 120 against a cam s , on the end of the shaft l ; the size of the teeth on the wheel 38 is to be such that the roller r , will take up as much paper as is required for each row of pins.

t , is a large drum on a hanging frame 41, on the frame a , with a contractile helical spring 42, behind it and around the roller q , and drum t , is an apron or band 43, that in sitting against one side of the roller r , gives

sufficient pressure to draw the paper with the pins in it and deliver it complete below.

It will be evident that the wheel e , may be made as two disks with corresponding notches in their edges instead of the flat faced wheel shown herein, and also it will be seen that the jaw 17 may have slight cavities on its upper side into which the pins fall.

10 I am aware that a wheel has been used to feed the pins down successively; but I am not aware of any wheel having been made that brings a row of pins to the proper place and then drops them by the withdrawal of

15 the circular slide 10.

I am aware that the fingers i^2 , have been used to force pins into paper, and as this part is nearly the same as the means used

in the process of sticking by hand, is old, and forms no part of my claim. 20

What I desire to secure by Letters Patent is—

I claim the circular guard e^1 , and circular slide 10, in combination with the wheel e , and spring f^2 , or its equivalent whereby 25 the pins are brought from the conductor and dropped at the required place as described and shown.

In testimony whereof I have hereunto set my signature this twenty fourth day of May 30 one thousand eight hundred and fifty two.

JOHN B. TERRY.
